US00D985243S

(12) **United States Design Patent** (10) **Patent No.:** **US D985,243 S**
(45) **Date of Patent:** **** May 9, 2023**

(54) **SHOE DEVICE**

- (71) Applicant: **Riomar IP, LLC**, Pampa, TX (US)
(72) Inventor: **William Lange Sykes**, Vero Beach, FL (US)
(73) Assignee: **Riomar IP, LLC**, Pampa, TX (US)
(**) Term: **15 Years**
(21) Appl. No.: **29/775,477**
(22) Filed: **Mar. 23, 2021**

Related U.S. Application Data

- (62) Division of application No. 29/666,027, filed on Oct. 9, 2018, now Pat. No. Des. 914,337, which is a division of application No. 29/548,243, filed on Dec. 11, 2015, now Pat. No. Des. 834,290, which is a division of application No. 29/472,421, filed on Nov. 12, 2013, now Pat. No. Des. 748,390.

CLAIM

The ornamental design for a shoe device, as shown and described.

DESCRIPTION

FIG. 1 is a perspective view of a shoe device, showing my new design, shown in reduced scale;

FIG. 2 is a perspective view thereof, shown without the shoe for ease of illustration, with one of the pins in uninstalled condition;

FIG. 3 is a perspective view thereof, shown without the shoe for ease of illustration;

FIG. 4 is a top plan view thereof, shown without the shoe for ease of illustration;

FIG. 5 is a bottom plan view thereof, shown without the shoe for ease of illustration;

FIG. 6 is a front elevation view thereof, shown without the shoe for ease of illustration;

FIG. 7 is a rear elevation view thereof, shown without the shoe for ease of illustration;

FIG. 8 is a right side elevation view thereof, shown without the shoe for ease of illustration; and,

FIG. 9 is a right side perspective view thereof, shown in reduced scale.

The broken lines in the figures illustrate the portions of the design that form no part of the claimed design.

1 Claim, 3 Drawing Sheets
